UNITED STATES PATENT OFFICE.

SAMUEL J. TURNER, OF CHICAGO, ILLINOIS, ASSIGNOR OF ONE-HALF TO OTTO RABE,
OF WILMETTE, ILLINOIS.

STRAP-FASTENER-OPERATING APPLIANCE.

1,319,127.

Specification of Letters Patent.

Patented Oct. 21, 1919.

Application filed March 7, 1919. Serial No. 281,127.

To all whom it may concern:

Be it known that I, SAMUEL J. TURNER, a citizen of the United States, residing at Chicago, in the county of Cook and State 5 of Illinois, have invented certain new and useful Improvements in Strap-Fastener-Operating Appliances, of which the following is a specification.

The present invention concerns novel and 10 serviceable means for deforming or distorting the overlapped end of a metal band or strap and a fastening clip fitted over them, whereby the parts will be so firmly and securely held or interlocked together that they 15 cannot become separated or detached in service. The bands or straps referred to are those used for binding boxes, cartons, or similar containers to effectively hold them from spreading or coming apart during the rough 20 treatment received in transit and otherwise.

As is usual in fastener applying or deforming structures of this general character, the device includes a coöperating die and associated punch with suitable means for actuating 25 them with the expenditure of a comparatively small amount of manual effort. One aim of this invention is the provision of an appliance of this type in which the punch and die are of such shape or form 30 that they can be easily and economically produced and will withstand the strains and stresses to which they are subjected without breaking, shipping, or otherwise becoming damaged. A further object of the invention 35 is the production of such an apparatus with its parts so formed and related to one another that great leverage on the punch can be had whereby the device is easily operated.

With the attainment of these and other desirable objects in mind I have produced a 40 convenient embodiment of the invention illustrated in the accompanying drawing and described in detail below. In this drawing, forming a part of this specification, like 45 reference characters refer to the same parts throughout the several views.

In such drawings:

Figure 1 is a central, longitudinal, vertical section through the device;

50 Fig. 2 is a plan view of the structure;

Fig. 3 is an end view of the same on an enlarged scale;

Fig. 4 is a face view of the overlapped

ends of a metal band or strap and their associated clip fastener; and

Fig. 5 is an edge view of the parts illustrated in Fig. 4.

It will be apparent from these drawings that the device comprises a main lower arm or primary supporting member 10 having a 60 depending lug or leg 11 at one end adapted to rest on the body around which the metal band or ribbon to be fastened extends. Secured by a plurality of screws 12, 12 to the bottom of the enlarged opposite end portion 65 of said member is a die-block 13 reduced in thickness at 14 thus providing a transverse shoulder 15 and having also a beveled front or end edge 16 to facilitate its introduction or insertion under the stretched or 70 tightened band or strap. Cut in the top of this part of decreased thickness is a straight groove 17 positioned centrally and disposed lengthwise the apparatus as a whole. A punch 18 is slidable toward and from the 75 die-block being guided in its reciprocations by the upright, apertured, cross-wall 19 of the part 10 and a removable end-plate 20 held to the element 10 by a plurality of screws 21, 21. This punch has a pair of 80 opposed alined teeth 12, 12 oppositely tapered lengthwise the device at 23 but having straight, vertical end surfaces 24, 24 forming extensions of the faces of the main body of the punch.

Such punch is automatically raised away from the associated die-block by a leaf-spring 25 fastened to the member 10 near one end by a screw 26 and extended through the aperture 27 of wall 19 into a recess or 90 cabinet 28 in the punch, this spring being supplemented or associated in its punch elevating function by a coil-spring 29 pressing upwardly against its undersurface.

To depress the punch and cause its beveled lugs to enter the die groove, a bent lever 30 is fulcrumed or hinged near one end of a fixed shaft 31 supported in spaced upstanding ears 32, 32 forming parts of the element 10. The longer leg of such punch-operating lever is bent downwardly somewhat at 33 as shown in Fig. 1, and coacting with this part is an antifriction roller 40 mounted on the short arm 34 of a bell-crank lever 35 of which the part 36 constitutes an 100 operating handle. Such bell-crank member

is fulcrumed on a cross pin 37 extending across the hollowed out or channel upper part of the member 10, so that to some extent the bell-crank lever is accommodated 5 and received in such member.

To positively limit the downward travel of the punch and also the closing action of handle 36, element 10 is equipped with an adjustable screw stop or abutment 38 adapted to engage a boss or lug 39 cast on the 10 under side of the transversely-curved handle 36.

To permit adjustment or control of the action of lever 30 on the reciprocatory punch 15 a screw 41 projects through a threaded hole in the lever, engages the top surface of the punch, and is fitted with a lock-nut 42.

The operation of the appliance is as follows: Assuming that the device has been 20 fitted or applied over the overlapped ends 50 and 51 of the stretched or tightened metal strap or band and the associated metal clip or fastener 52 with these parts brought into proper relation by bearing against the 25 shoulder 15, then the handle 36 is pressed down from its full line position in Fig. 1 to the dotted line position, thus bringing about the descent of the punch through the medium of the intermediate bent lever 30. 30 This movement of the punch teeth 22, 22 in coöperation with the side walls of the groove of the die cuts pairs of spaced slits 53, 53 in the opposite edges of the band ends and its fastener clip. At the same time these 35 beveled or tapered lugs or teeth bend down into the groove the tongues of metal 54, 54 between the slits thus so securely interlocking the three parts, band ends and clip, that they can not be pulled apart or separated under the strains to which the band or 40 strap is subjected. As soon as handle 36 is released it rises as does also the punch under the lifting action of the companion springs 25 and 29.

45 It will be understood that by bending lever 30 as shown a substantial and adequate range of movement of the punch may be had without sacrificing any of the desired leverage effect. It will be understood, furthermore, that when the handle 36 is depressed the leverage on the punch is increased by reason of the angular relation of the two arms of the bell-crank and also because the point of contact of arm 34 with 50 lever 30 progressively recedes from the fulcrum pin of the latter.

Within the scope of the appended claims many changes and modifications in the structure shown and described may be indulged 60 in all falling within the novel principles on which the invention is based and accordingly it will be understood that the invention is susceptible of fairly widely differing embodiments all incorporating the important and valuable features thereof.

I claim:

1. In a fastener deforming appliance of the character described, the combination of a support, a grooved die mounted thereon adapted to support a plurality of superposed bodies with the groove disposed crosswise of their lengths, a punch guided by and 70 slideable in said support toward and from said die, and means to operate said punch, the latter having oppositely - beveled teeth adapted to enter said die groove, the sides only of the punch co-acting with the walls of the die groove to provide parallel slits in the superposed bodies operated upon, the beveled faces of such teeth pressing the tongues of the material between said slits out of their original planes, thereby locking said bodies together by such laterally disposed deformed tongues, substantially as described.

2. In a fastener deforming appliance of the character described, the combination of a support, a die thereon, a punch guided by and slideable in said support toward and from said die, and means to operate said punch including a lever fulcrumed on said support and having a surface oblique to the longitudinal axis of the lever, and a bell-crank lever fulcrumed on said support having one of its arms bearing on said surface to operate the lever and punch, substantially as described.

3. In a fastener-deforming appliance of the character described, the combination of a support, a die thereon, a punch guided by and slideable in said support toward and from said die, and means to operate said punch including a lever fulcrumed on said support and having a surface oblique to the longitudinal axis of the lever, and an operating bell-crank lever fulcrumed on said support having a shorter arm equipped with an anti-friction roller bearing on said lever surface to operate the lever and punch, substantially as described.

4. In a fastener deforming appliance of the character described, the combination of a support, a grooved die mounted thereon adapted to support a plurality of superposed bodies with the groove disposed crosswise of their lengths, a punch guided by and slideable in said support toward and from said die, the punch having oppositely - beveled teeth adapted to enter said die groove, the sides only of the punch teeth co-acting with the walls of the die groove to provide parallel slits in the superposed bodies operated upon, the beveled faces of such teeth pressing the tongues of material between such slits out of their original planes thereby locking said bodies together by such laterally-disposed deformed tongues, and means to operate said punch including a lever fulcrumed on said support and having a surface oblique to the longitudinal axis of the lever, and an operating bell-crank lever fulcrumed on said sup- 120 125 130

port having one of its arms bearing on said surface to operate the lever and punch, substantially as described.

5. In a fastener deforming appliance of the character described, the combination of a support, a grooved die mounted thereon adapted to support a plurality of superposed bodies with the groove disposed crosswise of their lengths, a punch guided by and slidable 10 in said support toward and from said die, the punch having oppositely-beveled teeth adapted to enter said die groove, the sides only of the punch teeth co-acting with the walls of the die groove to provide parallel 15 slits in the superposed bodies operated upon, the beveled faces of such teeth pressing the

tongues of material between such slits out of their original planes, thereby locking said bodies together by such laterally-disposed deformed tongues, and means to operate such 20 punch including a lever fulcrumed on said support and having a surface oblique to the longitudinal axis of the lever, and a hook-shaped operating bell-crank lever fulcrumed on such support having one of its arms 25 shorter than the other and equipped with an anti-friction roller bearing on said lever surface to operate the lever and punch, said operating-lever being shaped to receive between its two arms the part of the lever having the 30 oblique surface, substantially as described.

SAMUEL J. TURNER.
